UNITED STATES PATENT OFFICE.

ROBERT F. BEARDSLEY, OF KALAMAZOO, MICHIGAN, ASSIGNOR TO KALAMAZOO CORSET COMPANY, OF KALAMAZOO, MICHIGAN.

VENTILATING-SECTION FOR CORSETS.

1,252,990.

Specification of Letters Patent.

Patented Jan. 8, 1918.

Application filed October 4, 1917. Serial No. 194,753.

To all whom it may concern:

Be it known that I, ROBERT F. BEARDSLEY, a citizen of the United States, residing at the city and county of Kalamazoo, State 5 of Michigan, have invented certain new and useful Improvements in Ventilating-Sections for Corsets, of which the following is a specification.

This invention relates to improvements in 10 ventilating sections for corsets and similar garments.

The main objects of this invention are:

First, to provide an improved ventilating section for corsets or similar garments which 15 may be rapidly and economically formed by machine work.

Second to provide an improved garment having ventilating sections which is neat in appearance and of light weight and at the 20 same time very strong and durable.

Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated in 30 the accompanying drawing, forming a part of this specification, in which:

Figure I is a detail elevation of a corset embodying the features of my invention.

Fig. II is a detail elevation of the ventilating strip employed by me.

Fig. III is an enlarged detail section on a line corresponding to line 3—3 of Fig. I.

Fig. IV is an enlarged detail section on a 40 line corresponding to line 4—4 of Fig. II.

Fig. V is a perspective view of one of the cross pieces of the ventilating strip.

In the drawing similar reference characters refer to similar parts throughout the 45 several views, and the sectional views are taken looking in the direction of the little arrows at the ends of the section lines.

I have illustrated only such portions of a garment as will enable the understanding 50 of my invention. It will be understood that my improved ventilating insert may be inserted at the front or at the back or otherwise as may be desired.

The fabric parts and stitching are shown

conventionally for convenience in illustration.

Referring to the drawing, 1, 1, represent sections of the body of a garment, such as a corset, having opposed spaced edges. As one of the aims is to secure a light, cool garment, these are preferably of a single thickness of material. A ventilating insert is introduced between these sections 1, 1, comprising spaced cross pieces 2, to the ends of which are secured longitudinal insert 65 strips 3. These cross pieces are preferably formed of two strips of fabric 4, 4, having infolded edges 5, the strips being secured together by longitudinal rows of stitches 6 adjacent their edges. In practice these 70 strips are sewed in long pieces and cut to proper lengths. The longitudinal strips 3 are formed of pieces of tape or fabric 7, 7, having infolded edges 8, the ends of the cross pieces 2 being disposed between the 75 inner edges of the longitudinal strips, the pieces forming the longitudinal strips and the cross pieces being secured together by rows of stitching 9 at the inner edges of the longitudinal strips.

The edges of the body sections 10 are disposed between the outer edges of the longitudinal strips 3 and secured by rows of stitching 11 at the outer edges of the strips. This effectively unites the parts and when 80 united the garment has a finished and attractive appearance, the parts being united without producing any objectional thickness of material at any point.

It is possible to manufacture the insert 90 strips by machinery, a machine suitable for the purpose being shown in my co-pending application filed October 10, 1917, Serial No. 193,727. The insert strips may be assembled with the body sections, by an ordinary sewing machine used in the manufacture of corsets and the like, which is of special advantage, as it results in economy in manufacture.

I have not attempted to illustrate or describe various adaptations of my improvements, as I believe the disclosure made will enable those skilled in the art to embody or adapt the same as may be desired.

Having thus described my invention, what 105 I claim as new and desire to secure by Letters Patent, is:

1. In a corset, the combination of two

- body sections thereof having spaced opposed edges, and an insert comprising spaced cross pieces formed of strips of fabric having infolded edges secured together by longitudinal rows of stitches at each edge, and pairs of longitudinal strips having infolded edges between the inner edges of which the ends of said cross strips are disposed and secured by rows of longitudinal stitches at the inner edges of said longitudinal strips, the edges of said body sections being disposed between and secured to said longitudinal strips by rows of longitudinal stitches at their outer edges.
- 10 2. In a corset, the combination of two body sections thereof having spaced opposed edges, and an insert comprising spaced cross

pieces of fabric, and pairs of longitudinal strips between the inner edges of which the ends of said cross strips are disposed and 20 secured by rows of longitudinal stitches at the inner edges of said longitudinal strips, the edges of said body sections being disposed between and secured to the outer edges of said longitudinal strips by rows of longitudinal stitches at their outer edges.

In witness whereof I have hereunto set my hand and seal in the presence of two witnesses.

ROBERT F. BEARDSLEY. [I. S.]
